UNITED STATES PATENT OFFICE.

JOHN BAKER, OF HANDSWORTH, BIRMINGHAM, ENGLAND.

ETCHING APPARATUS.

Application filed September 29, 1926, Serial No. 138,463, and in Great Britain October 10, 1925.

This invention relates to an improved method and means for treating zinc or other suitable printing plates by exposing them to the action of metallic acids subsequent to protecting the necessary parts from the action of the acid in order to obtain the requisite fine relief of the subject to be printed. Various methods of achieving this result have been in practice for a considerable time and the results are more or less successful. In some machines for mechanically obtaining this process of etching, the acid solution is agitated into a drifting spray, the plate to be etched being in the intense zone of the spray. Other spraying methods have been adopted, but unless a very expensive plant is employed the results are not always satisfactory. The object of this invention is to provide a means of etching metal plates by exposure to an acid, which does not require an expensive plant and which will be convenient and highly efficient in use. A further object of this invention is to protect the operator from the acid fumes.

According to this invention the method of applying the acid to the plate to be etched consists in spraying a number of jets over the surface of the plate. The jets can be obtained by submerging into the acid a perforated surface, preferably composed of a material not subject to corrosion by the acid solution.

Briefly the preferred embodiment of this invention may be said to consist in a receptacle for the acid solution, a plate having a large number of perforations therein, the said plate being disposed within the said receptacle and having means associated with it whereby the plate to be etched can be secured in spaced relationship above it, mechanism being provided for raising and lowering the perforated plate out of and into the acid solution at a speed sufficient to ensure the acid solution being sprayed in jet form through the perforations over the surface of the plate to be etched.

The mechanism above referred to may conveniently consist of a pair of horizontal bars disposed above the receptacle and carrying by depending vertical rods the perforated plate, the said rods passing through guides in the top or cover of the receptacle, and coiled springs being interposed between the bars and the top of the receptacle, the said

springs normally holding the perforated plate in the raised position, the influence of the springs being periodically and quickly intermittently overcome to submerge the perforated plate, by the rotation of a cam engaging a lever connected indirectly to the said bars.

To drive out noxious fumes, for instance nitrogen peroxide fumes, which accumulate in the acid receptacle, or to quickly aerate the acid solution when free acids are used and in the event of the receptacle being enclosed by a cover, for instance a glass cover, an aerating pump is provided which abstracts the fumes from the receptacle and draws air into the receptacle. This pump may be of any well known type, for instance bellows operated in unison with the mechanism for moving the perforated plate.

In order that this invention may be clearly understood and readily carried into effect I have appended hereto two sheets of drawings, somewhat diagrammatically illustrating same and wherein:

Fig. 1 is a perspective view of the complete apparatus.

Fig. 2 is a perspective view showing the top of the acid receptacle and the aerating pump.

Fig. 3 is an enlarged detail view of the acid receptacle and associated parts showing a modified construction, and

Figs. 4, 5 and 6 show different methods of providing perforations in the perforated plate.

Referring to Figures 1 and 2 of the drawings, the plate to be etched is indicated by the reference numeral 1, and it will be seen that it is supported in a horizontal plane above and parallel to a perforated plate 2 which is adapted to be intermittently submerged into the acid solution contained in an acid-proof bath 3. The bath 3 is flanged around its upper edge as at 4 to support a three sided top plate or cover 5 which accommodates a hingedly supported frame 6 carrying a glass window 7 whereby the bath may be closed but its interior be visible to the operator. In Fig. 1 the frame 6 is shown open, and in Fig. 2 it is shown closed.

The perforated plate 2 has a surrounding shallow wall 2^a so that it has a tray like appearance, and it is suspended from four vertical rods 8 slidably through guides in the cover 5 and secured at their upper ends to

a pair of horizontal bars 9 between which and the top 5 are disposed coiled springs 10 which normally maintain the perforated plate 2 raised above the level of the acid solution in the bath 3.

It will be apparent that if the perforated plate 3 is quickly submerged into the acid solution the solution will be sprayed through the perforations in the plate and will play upon the surface of the etching plate 1. According to the speed of the submersion and the number of times it is effected depends the degree of relief effect obtained by the action of the acid upon the plate 1, accordingly a suitable mechanism is provided for enabling an operator to determine these factors. A simple and suitable form of mechanism for this purpose is shown in the drawings and consists of an axially rotatable shaft 11 supported in bearings 12 alongside the bath 3. One end of this shaft is provided with a crank 13 for manual operation, or may be driven by a belt and pulley or other known form of drive. The other end 25 of the shaft 11 carries a cam or if desired an eccentric 14 with the periphery of which engages a roller 15 carried by the free end of an arm 16 pivotally supported at one end 17 and connected by a vertical link 18 to a rod 19 extending from the centre of a yoke or U-shaped member 20 pivotally connected at its cranked ends 21 to uprights 22 carried by the top 5.

To enable the amount of submersion of the perforated plate 2 to be predetermined the link 18 has a number of holes 18^a to receive the pivot pin 23 of the arm 16, whilst the uprights 22 if desired may be provided with a number of holes 24 to receive the cranked ends 21 of the member 20.

The free end of the rod 19 is connected by a pivot pin 25 to the upper end of a rod 26 pivotally connected at its lower end to a bellows or other suitable exhauster 27 which by means of a conduit 28 communicates with the interior of the bath 3, with a consequent automatic aeration of the bath 3 during the operation of the plant. The rod 19 can be adjustably connected to the arm 26 by providing a number of holes 26^a to receive the pin 25.

The bath 3 and the other parts of the plant are carried by a suitable frame 29 having a shelf 30 to support the exhauster 27. A coiled spring 31 connected at one end by a rod 32 to the arm 16, and at its other end to an anchoring rod 33 maintains proper engagement of the free end of the arm 16 with the cam 14.

60 In the modified construction shown in Fig. 3, the perforated plate 2 is provided at opposite ends with downwardly extending walls 2^a and is fixed in the acid bath in the position shown in such a manner as to form 65 between the walls 2^a and the end walls of

the bath 3 rectangular chambers which communicate with the space beneath the plate 2 round the lower edges of the walls 2^a. The rectangular chambers so formed accommodate pistons or plungers 3^a which are fixed to vertical rods 8^a sliding in guides in the cover of the acid receptacle similarly to the rods 8 shown in Fig. 1. The rods 8^a are actuated in the same way as the rods 8 of Figure 1 and the movement of the plungers 3^a causes acid to be forced through the perforations in the plate 2 upon the surface of the plate to be etched, which is carried on the plate 2 by means of supports (not shown) similar to those shown on the plate 2 in Fig. 1.

My invention obviates many defects arising out of the use of existing known forms of etching plant, inasmuch as it ensures a rapid and regular application of the acid to the plate to be etched, it protects the operator from the noxious fumes from the acid, and the waste in acid is reduced appreciably.

The perforations in the plate 2 may take various forms and can be obtained in different manners, for instance in Fig. 4, the plate 2 is shown with conical or jet like perforations 34. In Fig. 5 the perforations are obtained by superimposing a suitable number of plates 35, in which holes 36 are provided so arranged that when the plates 35 are correctly secured against each other the holes 36 are arranged in sets on common axes, the holes in each set being stepped in diameter the smaller diameter being uppermost. In Fig. 6 a still further modified form of perforation is shown in the form of a downwardly and outwardly flared hole 37 the upper end being very restricted in diameter and if desired disposed in a boss 38. The number, location and dimensions of the perforations can be varied by having interchangeable plates 2.

The jets may be forced upwards with greater power by increasing the effective thickness of the plate 2, by adding to the base of the plate a moulded counterpart thereby increasing the length of the perforations and, according to the level of the acid, obtaining a longer compression action on the acid. For instance in Fig. 5 the lower plate could be considered as an additional counterpart.

I claim:—

1. Apparatus for etching zinc and other plates comprising an acid receptacle, means for supporting the plate to be etched above the level of the acid in said receptacle, a perforated plate in said receptacle disposed approximately parallel to the surface of the acid, reciprocating means in said receptacle for forcing the acid through said perforated plate, to direct a number of jets upon the surface of the plate to be etched, a reciprocating exhauster for withdrawing fumes 120

from said acid chamber and an operative connection between said reciprocating means and exhauster.

2. Apparatus for etching zinc and other plates comprising an acid receptacle, means for supporting the plate to be etched above the level of the acid in the said receptacle, a perforated plate in said receptacle disposed approximately parallel to the surface of the acid reciprocating means in said receptacle having a lifting stroke for drawing acid through said perforated plate and a forcing stroke for forcing said acid through said perforated plate to direct a number of jets upon the surface of the plate to be etched, spring means acting on said reciprocating means, to effect the forcing stroke thereof and a cam device acting on said recipro-

cating device against said spring means for repeatedly effecting the lifting stroke thereof and then releasing said spring means for operation.

3. Apparatus for etching zinc and other plates comprising an acid receptacle, means for supporting the plate to be etched above the level of the acid in said receptacle, reciprocating means in said receptacle for directing jets of acid intermittently upon the surface of the plate to be etched, spring means for moving said reciprocating means in one direction and a rotary cam for repeatedly moving said reciprocating means in the opposite direction and then releasing the same.

JOHN BAKER.
